[57] CLAIM

The ornamental design for a cover for battery anti-theft control module, as shown and described.

DESCRIPTION

FIG. 1 is a left, top, front perspective view of a cover for battery anti-theft control module embodying our new design;

FIG. 2 is a top plan view thereof;

FIG. 3 is a front elevational view thereof, the rear elevational view being a mirror image of the front elevational view shown;

FIG. 4 is a left side elevational view thereof;

FIG. 5 is a right side elevational view thereof;

FIG. 6 is a left, top, front perspective view of a second embodiment;

FIG. 7 is a top plan view thereof;

FIG. 8 is a front elevational view thereof, the rear elevational view being a mirror image of the front elevational view shown;

FIG. 9 is a left side elevational view thereof; and,

FIG. 10 is a right side elevational view thereof.

The broken line representations of caps in FIGS. 1-10, of a slot in FIGS. 1, 2, 6, and 7, of edges in FIGS. 1-6 and 8-10, and of a battery in FIGS. 1 and 6, are for the purposes of illustration only, and form no part of the claimed design.
